INVENTOR:
JOHN E. MITCHELL

By Bruce S. Elliott

ATTORNEY.

UNITED STATES PATENT OFFICE

JOHN E. MITCHELL, OF DALLAS, TEXAS

COTTON THRESHING CYLINDER

Application filed November 6, 1930. Serial No. 493,764.

The general object of this invention is to provide a novel cylinder for use in cleaning or threshing cotton.

Devices of this character are used in cotton cleaning machines for loosening up the trash, hulls and other extraneous matter so that it may be screened out or in some other way separated from the cotton. Such devices also operate to break open tight bolls so as to enable extracting saws to separate the cotton from the trash and hulls.

As heretofore constructed all of these threshing or cleaning cylinders are in the form of drums having a continuous periphery, and provided with spikes or pins secured in and projecting from this periphery.

In one type of threshing cylinder, threaded pins are screwed into the surface of a wooden drum. This presents an unsatisfactory construction for the reason that the pins when coming into contact with foreign matter such as stones, pieces of metal, and the like, which often are found in the seed cotton delivered at the gin, easily split the wood.

The wooden drum is also objectionable in that it will not stay in running balance; it is difficult to hold in proper shape and to replace wooden portions when damaged.

Another type of threshing cylinder is in the form of a hollow steel drum with shouldered pins riveted through the walls of the drum. This type of cylinder is objectionable in that the entire cylinder must be replaced if too many of the pins or spikes become broken or damaged. It is also difficult to construct, especially in the smaller diameters, and is further objectionable in the tendency for trash to accumulate inside the drum.

My invention is characterized by the fact that the threshing cylinder is of skeleton form, and hence very light in proportion to its strength, especially as compared with former types of threshing cylinders. Furthermore, this form of construction lends it self to replaceable parts carrying the pins or spikes, and to the prevention of accumulation of cotton, trash, etc. inside the cylinder.

There are certain features of construction which also enter into the novelty of the cyl-

inder, but these will be better understood from the detailed description of the invention to follow.

In the accompanying sheet of drawing illustrating the invention:

Fig. 1 is a broken, side elevation of a threshing cylinder constructed according to my invention; and

Fig. 2 is a cross-sectional view taken on the line 2—2 of Fig. 1.

Referring now to the drawing the numeral 1 indicates the shaft of the cylinder on which are mounted a series of spiders 2 on the outer sides of which are secured four angular spike-bars 3. In practice I employ seven of the spiders 2, set on nine inch centers along the shaft 1. Each of these spiders has a hub 4 for mounting the spider on the shaft, and the spider is secured on the shaft by means of a set screw 5 screwed through said hub and engaging at its inner end the surface of shaft 1.

Each of the spiders 2 is of the shape shown in Fig. 2, that is to say, it is provided with four relatively narrow flat sides 6, a straight edge 7 extending inwardly from one end of each of the flat sides 6 parallel to a radial line drawn through the center of its hub, and an inclined side 8 extending from the bottom of each straight edge 7 to the end of the adjacent flat side 6 opposite to that from which its straight edge 7 extends.

Each of the angular spike bars 3 consists of a flat rectangular member, or bar proper, 9, from one side of which and formed integral therewith, extends a side member or shield 10. The bar portion 9 of each of the spike bars is of considerably greater thickness than the side member or shield 10 thereof, and is apertured at intervals throughout its length to receive a series of shouldered spikes 11, which are preferably riveted in place, as indicated at 12.

The spike bars 3 are adapted to be mounted on the spiders 2 to form the periphery or outer wall of the threshing cylinder. To this end, the bar portion 9 of each spike bar is seated on one of the lines of flat sides 6 of the spiders 2 and its side member or shield 10 will rest upon the corresponding inclined sides 8 of the series of spiders, as clearly il-

lustrated in Fig. 2. To secure the spike bars in place, I provide each of the spiders 2 with an apertured flange 13, projecting at right angles to the body of the spider at each of 5 the flat sides 6, and pass bolts 14 through the bar portions 9 of the spike bars and through the apertures in said flanges, and secure said bolts in place by means of nuts 15.

From the foregoing description it will be 10 seen that the sides 10 of the angle bars form shields, and with the cylinder rotating in the direction indicated by the arrow in Fig. 2, these shields prevent any cotton or trash from getting into the interior of the cylinder. In 15 other words, any cotton or trash striking against the shields 10 is immediately thrown off by centrifugal action. The sides 10 of the angle bars not only prevent the accumulation 20 of cotton and trash inside the cylinder but they also greatly strengthen the cylinder against strains exerted in a direction toward the shaft, such strains being frequently met with as a result of blocks of wood, pieces of 25 iron and other foreign matter going into the machine with the cotton.

As has heretofore been pointed out, the peripheral side 9 of each angle bar is much thicker than the inclined side portion or shield 10. The reason for this is that 30 strength is especially needed where the spikes are riveted through the steel, as these spikes are constantly striking against pieces of wood, iron and other foreign matter mixed with the cotton. On the other hand, the side 35 portion or shield 10 does not have to withstand any such strains, and to make it of the same thickness as the peripheral side 9 would result in a very heavy and cumbersome cylinder.

40 From the foregoing it will be seen that my improved threshing cylinder can be made a great deal lighter, and will be less expensive to manufacture than the types of threshing cylinders heretofore used, without at the 45 same time sacrificing anything in necessary strength, while at the same time possessing the advantage of the closed type of cylinder in the respect of preventing the accumulation of cotton and trash inside the cylinder.

50 The spike bars 3 are, of course, replaceable, and should any of the spikes be broken off, or the spike bar itself be injured by impact with a heavy foreign body, it may readily 55 be removed by unscrewing the nuts 15 and a new spike bar inserted therefor.

I wish it understood that the invention is not limited to the precise shape and arrangement of parts illustrated in the drawing, al- 60 though this shows the preferred embodiment of the invention, but that various changes could be made in the form, construction and arrangement of parts without departing from the spirit of my invention as defined in 65 the appended claims.

I claim:

1. A cotton threshing cylinder comprising a shaft, a series of flat-sided spiders mounted thereon, a series of independent spike-bars mounted on flat sides of said spiders to form the outer wall of the cylinder, each of said spike-bars having a flat peripheral portion and an inwardly-directed straight side member forming a shield, the inner end of which terminates near, but 70 below the plane of the flat portion of an adjacent spike-bar, and a row of radial spikes secured in said peripheral portion.

2. A cotton threshing cylinder comprising a shaft, a series of flat sided spiders mounted thereon, a series of independent spike-bars mounted on flat sides of said spiders to form the outer wall of the cylinder, each of said spike-bars having a flat peripheral portion and an inwardly-directed straight side member, of greater width than said peripheral portion, the inner end 80 of which terminates near, but below the plane of the flat portion of an adjacent spike-bar, and a row of radial spikes secured in said peripheral portion.

3. A cotton threshing cylinder comprising a shaft, a series of flat-sided spiders mounted thereon, a series of independent spike-bars mounted on flat sides of said spiders to form the outer wall of the cylinder, each of said spike-bars having a narrow, relatively thick, flat, peripheral portion and a relatively thin, inwardly directed, straight side member forming a shield, the inner end 85 of which terminates near, but below the plane of the flat portion of an adjacent spike bar, and a row of radial spikes secured in said peripheral portion.

4. A cotton threshing cylinder comprising a shaft, a series of flat sided spiders mounted thereon, a series of independently removable angular spike bars mounted on flat sides of said spiders to form the outer wall of the cylinder, one member of each spike-bar being flat and relatively narrow and thick, its flat side forming a peripheral portion of the cylinder, and the other member being straight, relatively thin and of greater width than the width of said peripheral member and inclined toward the shaft to form a shield, the inner end of which terminates near, but below the plane 100 of the peripheral portion of an adjacent spike bar, and a row of radial spikes secured in said peripheral member.

5. A cotton threshing cylinder comprising a shaft, a series of rectangular spiders mounted thereon each of which has four relatively narrow flat sides located opposite 115 each other, the flat sides at corresponding points of the spiders being in the same plane, longitudinal spike bars removably mounted on said flat sides of the spiders to form the outer wall of the cylinder, each of said spike 120 bars being flat and relatively narrow and thick, its flat side forming a peripheral portion of the cylinder, and the other member being straight, relatively thin and of greater width than the width of said peripheral member.

bars having a flat portion removably secured to the spiders on an aligning set of the flat sides thereof and an inwardly directed straight side member forming a shield, the inner end of which terminates near, but below the plane of the flat portion of an adjacent spike-bar, and a row of radial spikes secured in the flat portions of each of said spike bars.

10 In testimony whereof, I have hereunto set my hand.

JOHN E. MITCHELL.
